(57) **CLAIM**

The ornamental design for a ligature resistant drinking fountain, as shown and described.

DESCRIPTION

FIG. 1 is a perspective view of a ligature resistant drinking fountain.

FIG. 2 is a front elevation view of the ligature resistant drinking fountain.

FIG. 3 is a back elevation view of the ligature resistant drinking fountain.

FIG. 4 is a left elevation view of the ligature resistant drinking fountain.

FIG. 5 is a right elevation view of the ligature resistant drinking fountain.

FIG. 6 is a top plan view of the ligature resistant drinking fountain; and,

FIG. 7 is a bottom plan view of the ligature resistant drinking fountain.

The broken lines in the drawings illustrate subject matter which forms no part of the claimed design.

1 Claim, 6 Drawing Sheets
